UNITED STATES PATENT OFFICE.

LARS W. BODINSON, OF AURORA, ILLINOIS, ASSIGNOR TO THE AMERICAN WELL WORKS,
OF AURORA, ILLINOIS, A CORPORATION OF ILLINOIS.

DEEP-WELL PUMP.

1,289,625.

Specification of Letters Patent. Patented Dec. 31, 1918.

Original application filed March 12, 1915, Serial No. 13,868. Divided and this application filed February 13, 1917. Serial No. 148,338.

To all whom it may concern:

Be it known that I, LARS W. BODINSON, a citizen of the United States, and a resident of Aurora, in the county of Kane, State of Illinois, have invented certain new and useful Improvements in Deep-Well Pumps, of which the following is a specification, reference being had to the accompanying drawings.

10 This invention relates to deep well pumps of the plunger type, and it has for its principal object the provision of a construction and arrangement by reason of which the pump rods and plungers may be readily 15 drawn upward out of operative position whenever desired for replacing or repairing the plungers. It is another object of my invention to provide such a construction in which one or more of the cylinders within 20 which the plungers operate may be raised to the surface with the plungers without the removal of the well casing, this result being attained preferably through the medium of the pump rods. It is still another 25 object of my invention to improve devices of this type in sundry details hereinafter pointed out. The preferred means by which I have accomplished my several objects are illustrated in the accompanying drawings 30 and are hereinafter specifically described. That which I believe to be new and desire to cover by this application is set forth in the claims.

In the drawings:

35 Figure 1 is a central vertical sectional view of the upper part of the pumping mechanism located at the bottom of the well;

Fig. 2 is a continuation downward of the view of Fig. 1; and

40 Fig. 3 is a continuation downward of the view of Fig. 2.

Referring to the several figures of the drawings in which corresponding parts are indicated by the same reference characters,

45 10 indicates a tubular pump rod surrounding a second pump rod 11 which is capable of being reciprocated relative thereto, the pump rods 10 and 11 being adapted for 50 operating the pumping mechanism hereinafter specifically described for forcing water upward through the well pipe 12. The pump rods 10-11 are to be reciprocated by

any suitable operating means, such operating means being preferably of the general type shown and claimed by Letters Patent of the United States, No. 1,124,295, issued on January 12, 1915, to The American Well Works, as the assignee of Matthew T. Chapman. By the use of the mechanism of this patent, the upward stroke of each pump rod will be caused to begin before the other pump rod reaches its uppermost position.

The construction of the pumping mechanism comprising the subject-matter of this application is along the general line of the mechanism shown and claimed in my application, Serial No. 13,868, filed March 12, 1915, of which prior application the present application is a division. This mechanism comprises an upper cylinder 13 having plungers 14-15 slidably mounted therein, and a lower cylinder 16 having plungers 17 and 18 slidably mounted therein. In the construction shown, the plungers 14 and 18 are 75 adapted to be reciprocated in unison by means of the pump rod 11, while the plungers 15 and 17 are reciprocated in unison by the tubular pump rod 10. The plungers 14 and 15 coöperate to force water upward 80 from the cylinder 13 through the well tube 12, while the plungers 17 and 18 coöperate for forcing water upward through the well tube 12 from the cylinder 16.

The means for connecting the plungers 14 and 18 with the pump rod 11 and the plungers 15 and 17 with the pump rod 10 comprises a cross-head 19 in the form of a spider secured by means of a coupling device 20 upon the lower end of the pump rod 11. 90 The cross-head or spider 19 has fixedly connected with it a pipe or cylinder 21 extending downward about a pump rod 22 also secured to the cross-head 19, the pipe or cylinder 21 being spaced away from the pump rod 22. A pipe 23 extends upward through the lower end of the pipe or cylinder 21, such pipe 23 being connected as hereinafter described with the pump rod 10. The lower end of the cylinder 21 is closed about the 100 pipe 23 by means of a coupling device 24 provided with a stuffing-box 25 of any suitable type. The coupling 24 is connected at its lower end portion with a sleeve 26 forming the inner shell portion of the plunger 14. A valve 27 is slidably mounted upon

the sleeve portion 26 of the plunger, being adapted to have its upward movement limited by the lower end portion of the coupling 24. The plunger 14 comprises radially-extending webs 28 by which the inner and outer shells of the plunger are connected, and comprises further suitable packing 29 secured upon the outer face of the outer shell. By the construction here described, 10 the plunger 14 is connected with the pump rod 11 so as to be reciprocated therewith.

The upper end of the pipe 23 has fixedly mounted thereon a coupling 30 in the form of a spider and provided at its upper end 15 portion with a cross-head 31. This cross-head is connected by means of bolts 32 with a cross-head 33 fixedly connected with the lower end of the pump rod 10. The bolts 32 preferably pass through suitable openings in the radially-extending arms of the cross-head 19, but this is not essential. As will be readily understood, the arrangement 20 of the parts is such that the cross-heads 31 and 33 are adapted to be reciprocated vertically with the pump rod 10 without interference with the normal vertical reciprocation of the cross-head 19 and the pump rod 11. The pipe 23 is connected at its lower end with the inner shell portion 34 of the 25 plunger 15, a similar pipe 35 being connected with the lower end of the portion 34 and extending downward therefrom. The plunger 15 is provided with a suitable valve 36 slidably mounted upon the inner shell 30 portion 34, the valve being limited in its upward movement by a suitable sleeve 37. The plunger 15 comprises radially-extending webs 38 which join the inner and outer shell portions, the outer shell portion being 35 40 provided with packing 39 of any suitable type.

The well tube 12 is provided at its lower end with a coupling device by which it is connected with the upper end of the cylinder 16. This coupling device comprises a sleeve 40 mounted upon the well tube 12, a sleeve 41 mounted upon the cylinder 16, and a plurality of webs 42 which hold the sleeves 40 and 41 in spaced relation to each other. The lower end of the cylinder 13 is provided with a closure member 43 comprising inner and outer shell members spaced relative to each other by means of webs 44. The closure member 43 tapers toward its lower end, having a snug fit within a correspondingly-shaped seat provided by the sleeves 40-41 of the coupling device above described. The closure member 43 is provided with an upwardly-opening valve 45 of any suitable type, and is also provided with packing 46 adjacent to the sleeve 41 and with packing 47 adjacent to the pipe 35 which has a working fit in the closure member 43.

65 The lower end of the pipe 35 within the

cylinder 16 is provided with a coupling device 48 which connects the lower end of said pipe with a sleeve 49 which comprises the inner shell member of the plunger 17. The coupling 48 is in the form of a cage, serving to leave the lower end of the pipe 35 open into the interior of the cylinder 16. By an inspection of the drawings, it will be seen that the cylinder 16 is thus in communication through the pipes 35 and 23, the 70 coupling 30, the pipe or cylinder 21, and the cross-head or spider 19 with the well tube 12 above the uppermost plunger. The plunger 17 is provided with suitable packing 50 between its inner shell member 49 and the pump rod section 22. This plunger is also provided with a suitable upwardly-opening valve 51 whose upward movement is limited by the coupling 48. The plunger comprises further radially-extending webs 52 joining 75 the inner and outer shell portions, the outer shell portion being provided with packing 53 of any suitable type in contact with the inner face of the cylinder 16.

The lower end of the pump rod 22 is secured by means of screw threads in the upper end of a sleeve 54 comprising the inner shell member of the plunger 18, a lock-nut 55 being employed for securing the plunger against working loose on said rod. The 90 plunger 18 comprises radially-extending webs 56 joining the inner and outer shell members, and the outer shell member is provided with suitable packing 57 in contact with the inner face of the cylinder 16. 95 A suitable upwardly-opening valve 58 is provided, limited in its upward movement by a collar 59 mounted upon the upper end of the sleeve 54.

The lower end of the cylinder 16 is provided with an upwardly-opening valve 60 adapted to close the lower end of the cylinder, the valve 60 being slidably mounted in a valve-cage 61 having a tapered seat in a sleeve 62 mounted upon the lower end of 100 said cylinder.

As will be readily understood, when the pump rods 10 and 11 are reciprocated vertically relative to each other, water is drawn upward into the cylinder 13 through the upwardly-opening valve 45, such water being admitted from the well through the closure member 43. This water is forced upward through the well tube 12, through the alternately opening and closing valves 36 and 27, this result being attained independently of the valve 45. At the same time water is being forced upward from the cylinder 16 by the coöperation of the cylinders 17 and 18. Such water is admitted through the upwardly-opening valve 60 and passes upward through the alternately opening and closing valves 58 and 51, passing upward through the coupling 48, the pipe 35, the pipe 23, the coupling 30, the pipe 21, and the spider 19 110 115 120 125 130

into the well tube 12 above the plunger 14. This result is attained independently of the valve 60.

Whenever it is desired for any reason to lift the pumping apparatus upward out of position in the well, this can be accomplished by drawing the pump rods 10 and 11 upward. By reason of the connection of the various plungers with the pump rods 10 and 11, such plungers will move upward immediately in response to an upward pull upon the pump rods. When the plunger 17, comprising in the construction shown the coupling member 48, comes into contact with the closure-member 43, such closure-member and the cylinder 13 carried thereby are caused to move upward with the pump rods and plungers, the cylinder 13 being thus lifted upward out of position relative to the well tube and relative to the cylinder 16.

What I claim as my invention and desire to secure by Letters Patent, is—

1. The combination of a well-pipe, a cylinder in said well-pipe, single-acting pumping means in said cylinder adapted to be reciprocated therein for forcing a supply of water upward through said well-pipe, and other single-acting pumping means adapted to be reciprocated in alinement with said first-named pumping means for forcing a separate supply of water into said well-pipe above said cylinder, said cylinder and said pumping means being adapted to be lifted together out of said well-pipe.

2. The combination of a well-pipe, a cylinder having a tapered seat in said well-pipe, single-acting pumping means in said cylinder adapted to be reciprocated therein for forcing a supply of water upward through said well-pipe, and other single-acting pumping means adapted to be reciprocated in alinement with said first-named pumping means for forcing a separate supply of water into said well-pipe above said cylinder, said cylinder and said pumping means being adapted to be lifted together out of said well-pipe.

3. The combination of a well-pipe, a coupling mounted on the lower end of said well-pipe, a cylinder having a tapered lower end seated in a correspondingly-shaped portion of said coupling, single-acting pumping means in said cylinder adapted to be reciprocated therein for forcing a supply of water upward through said well-pipe, and other single-acting pumping means adapted to be reciprocated in alinement with said first-named pumping means for forcing a separate supply of water into said well-pipe above said cylinder, said cylinder and said pumping means being adapted to be lifted together out of said well-pipe.

4. The combination of a well-pipe, a cylinder opening at its lower end into the well supported within said well-pipe, single-act-

ing pumping means in said cylinder adapted to be reciprocated therein for forcing a supply of water upward through said well-pipe, and other single-acting pumping means adapted to be reciprocated in alinement with said first-named pumping means for forcing a separate supply of water into said well-pipe above said cylinder, said cylinder and said pumping means being adapted to be lifted together out of said well-pipe.

5. The combination of a well-pipe, a coupling mounted on the lower end of said well-pipe, a cylinder in said well-pipe, a sleeve mounted on the lower end of said cylinder, said coupling and said sleeve being correspondingly tapered below said well-pipe and said cylinder whereby said cylinder is removably seated in said well-pipe, single-acting pumping means in said cylinder adapted to be reciprocated therein for forcing a supply of water upward through said well-pipe, and other single-acting pumping means adapted to be reciprocated in alinement with said first-named pumping means for forcing a separate supply of water into said well-pipe above said cylinder, said cylinder and said pumping means being adapted to be lifted together out of said well-pipe.

6. The combination of a well-pipe, a coupling mounted on the lower end of said well-pipe, a cylinder in said well-pipe, a valve-cage mounted on the lower end of said cylinder, said coupling and said valve-cage being correspondingly tapered below said well-pipe and said cylinder whereby said cylinder is removably seated in said well-pipe, said coupling being provided with an annular opening therethrough with which the opening through said valve-cage is adapted to register, single-acting pumping means in said cylinder adapted to be reciprocated therein for forcing a supply of water upward through said well-pipe, and other single-acting pumping means adapted to be reciprocated in alinement with said first-named pumping means for forcing a separate supply of water into said well-pipe above said cylinder, said cylinder and said pumping means being adapted to be lifted together out of said well-pipe.

7. In a deep well pumping mechanism, the combination of a cylinder, a second cylinder of approximately the same diameter removably secured above said first-named cylinder in alinement therewith, two plungers in each of said cylinders, and plunger rods connected with said plungers and adapted to reciprocate the lowermost plunger of each cylinder in unison with the uppermost plunger of the other cylinder, the plungers in the lower cylinder being adapted to be drawn upward out of said cylinder and serving to carry the upper cylinder also upward out of position.

8. In a deep well pumping mechanism,

the combination of a cylinder, a second cylinder of approximately the same diameter removably secured above said first-named cylinder in alinement therewith, 5 valved closure means for the lower end of said second cylinder, a plurality of plungers in each of said cylinders, and plunger-rods for reciprocating the plungers in each cylinder in operative relation to each other for 10 forcing water upward therefrom, the plungers in the lower cylinder being adapted to be drawn upward out of said cylinder and serving by engagement with said closure means to carry the upper cylinder also upward out of position.

9. In a deep well pumping mechanism, the combination of a cylinder, a second cylinder of approximately the same diameter above said first-named cylinder and in alinement 20 therewith, a plurality of plungers in each of said cylinders, and plunger-rods for reciprocating the plungers in each cylinder in operative relation to each other for forcing water upward therefrom, the plunger rods 25 and plungers being adapted to be drawn freely upward out of position in the well without the removal of the lower cylinder.

10. In a deep well pumping mechanism, the combination of a cylinder, a second 30 cylinder of approximately the same diameter above said first-named cylinder and in alinement therewith, a pumping means in each of said cylinders, and operating means for reciprocating said pumping means in 35 each cylinder in operative relation to each other for forcing water upward therefrom, said pumping means being adapted to be drawn freely upward out of position in the well without the removal of the lower cylinder.

11. The combination of a well-pipe, a cylinder opening at its lower end into the well supported within said well-pipe, pump-

ing means in said cylinder adapted to be reciprocated therein for forcing a supply of 45 water upward through said well-pipe, and other pumping means adapted to be reciprocated in alinement with said first-named pumping means for forcing a separate supply of water into said well-pipe above said 50 cylinder, said cylinder and said pumping means being adapted to be lifted together out of said well-pipe.

12. The combination of a well-pipe, a cylinder opening at its lower end connected 55 to the well support within said well-pipe, a plurality of pumping means adapted to be reciprocated therein for forcing a multiple supply of water upward through said well-pipe, and other pumping means adapted to 60 be reciprocated in alinement with said first-named pumping means for forcing a separate supply of water into said well-pipe above said cylinder, said cylinder and said pumping means being adapted to be lifted 65 together out of said well.

13. In a deep well pumping mechanism, the combination of a cylinder, a second cylinder removably supported above said 70 first-named cylinder, plungers in said cylinders respectively, plunger-rods for operating said plungers, and means adapted upon the withdrawal of said plunger-rods to lift said second cylinder therewith out of the well independently of said first named cylinder. 75

14. In a deep well pumping mechanism, the combination of a plurality of cylinders of equal diameter, plungers in said cylinders respectively, a discharge pipe leading up from said cylinders, and plunger-rods connected with said plungers for reciprocating them, said plunger-rods and plungers being removable from the well through said discharge-pipe.

LARS W. BODINSON.
